UNITED STATES PATENT OFFICE.

GEORGE C. CUMMINGS, OF EAST ORANGE, NEW JERSEY, ASSIGNOR TO WESTERN ELECTRIC COMPANY INCORPORATED, OF NEW YORK, N. Y., A CORPORATION OF NEW YORK.

TELEGRAPH SYSTEM.

Application filed December 20, 1919. Serial No. 346,370.

To all whom it may concern:

Be it known that I, GEORGE C. CUMMINGS, a subject of the King of Great Britain, residing at East Orange, in the county of Essex, State of New Jersey, have invented certain new and useful Improvements in Telegraph Systems, of which the following is a full, clear, concise, and exact description.

10 This invention relates to telegraph systems and particularly to such systems where telegraphic signals are adapted to be transmitted over a line to which telephone apparatus is also connected.

15 The principal object of the invention is the provision of a telegraph system wherein means is provided for preventing telegraphic signals from interrupting or disturbing the operation of the telephonic apparatus which 20 may be associated with a line over which telegraphic signals are also traversing.

25 A second object of the invention is the provision of means for suppressing disturbing harmonic frequencies created during the transmission of alternating current signals.

30 Another object of the invention, is to provide in conjunction with a system of the character as above referred to, means for preventing the absorption of the telegraphic signaling currents by the composite equipment connected with the line.

35 Another object of the invention, is to provide means for excluding from the alternating current telegraph apparatus currents other than those transmitted from the alternating current source.

40 A conversation carried on between two parties over a line over which telegraphic signals are being simultaneously transmitted has been found to be interfered with due to the presence of currents of a frequency considerably higher than the fundamental frequency generated at the alternating current source. This causes considerable noise in 45 the telephone circuit and thereby materially impairs the efficiency of the system. But in the present system this difficulty has been overcome by the introduction of suppression filters between the alternating current source and the line. These filters have the inductance and capacitance values thereof so chosen as to suppress the currents of a frequency other than the fundamental fre-

quency of the generated current. It is thus evident that the characters transmitted from 55 a telegraphic key connected in series with the alternating current source, as sent over the line, will not be distorted and at the same time, render the balancing of the line much easier.

60 In a system in which both alternating and direct current signals are transmitted, the direct current signals tend to affect the alternating current receiving device and thereby make it difficult to actually detect the alternating current signals. This, in the present invention, is overcome by means of the insertion of a filter in bridge of a coil of the transformer which connects the alternating current receiving circuit with the line. The 65 inductance and capacitance values of this filter are so chosen as to filter out or suppress currents of a frequency other than those of the frequency as generated at the alternating current source.

70 As a means for suppressing the higher harmonics generated at the alternating current source there is inserted between the source and the point of its connection with the line a filtering network which prevents the higher harmonics from being transmitted to the line and telephone apparatus associated therewith. The alternating current receiving apparatus is rendered opaque to 75 direct current signals by the provision of a filtering network connected in bridge of the circuit connecting the alternating current receiving apparatus with the line. In preventing the alternating current signals from 80 interfering with the direct current signals and the phantom circuit, there is interposed between these two parts and the point of their connection with the line, another filtering network for excluding currents of the 85 frequency as generated at the alternating current source.

90 It is thought that a more definite understanding of the invention may be had from the following description when considered in conjunction with the accompanying drawing, in which Fig. 1 shows a telephone line over which both direct and alternating current telegraphic signals are adapted to be superimposed. Fig. 2 shows another embodiment of the invention in which there is 95 shown an alternative arrangement for con-

necting the telephone branch or composite equipment with the line. Fig. 3 shows another embodiment of the invention in which the alternating current receiving and transmitting means is inductively coupled with the telephone line. Fig. 4 shows the application of the invention to a grounded line; while Fig. 5 shows an alternative method of connecting the alternating current receiving

means, as employed in Fig. 4 with the line.

Referring now to the drawing, paying particular attention to Fig. 1, in which there is shown two line conductors 4 and 5 which form a metallic telephone circuit and upon which there is also adapted to be superimposed both direct and alternating current telegraphic signals. A direct current duplex equipment is connected with each of the conductors 4 and 5 only one of which is shown and are so arranged that it is possible to transmit direct current signals over both sides of the line. The line conductors terminate in a bridge 90 to which is inductively coupled the telephone circuit and the alternating current receiving and transmitting circuits. Each of the direct current duplexes is also connected with the line through a portion of this bridge. Connected in bridge of the circuit conductors forming a part of the previously referred to bridge are condensers 8, 9, 10 and 11 and an induction coil 7, the mid-point of the induction coil 7 being connected to ground for the purpose stated below. In shunt of the condensers 8 and 9 and the inductance 11 there is a second induction coil 6. At the middle point of the inductance 6 a lead is taken off which serves as one side of the phantom circuit while the middle point of the coil 7 is grounded for the purpose of protecting the phantom circuit from serious transmission losses and since it is connected with the direct current duplexes through the condensers 12 and 13, it prevents serious crossfire between the signals being transmitted over each of the conductors 4 and 5.

The direct current duplex equipment is, as shown, of the standard type and comprises a sending key 14 for connecting with the apex of the ratio arms 15 and 16 a source of potential the polarity thereof being adapted to be varied. In circuit with the key 14 and the apex of the ratio arms 15 and 16 there is connected an inductance 17 and a condenser 18 which serve to round off the direct current telegraph signals and is often times termed a noise killer. There is also provided the usual polarized relay 19 for controlling the operation of a receiving sounder such as 20 for enabling an operator to readily detect the signals as transmitted from a distant station.

An artificial line is connected with the ratio arms and is for the purpose as is well known to balance the line for taking care of

disturbances and other causes which tend to distort and interfere with signals transmitted over the line. An inductance 74 is inserted in series with the line and direct current duplex equipment which when taken with the condenser 12 tends to more completely round off the direct current signals. Since the direct current duplex arrangement does not form a part of the present invention and since the method of operation thereof is well known to those skilled in the art, a detailed description of this part of the system has been omitted.

As to the alternating current signals, a generator 21 for generating a current of approximately 80 cycles is employed in circuit with which is a transmitting key 22. This key is for the purpose of connecting the source of alternating current to the primary coil of a transformer 23 through which the current is transformed to the secondary coil thereof and then to the primary coil of a transformer 24. A set of inductive resistances and condensers such as 25 and 26 is interposed between these two transformers and make up what is known as an electric filter. The resistances are connected in series with the two coils of the transformers 23 and 24 respectively, while the condensers are connected in bridge thereof. In the generation of alternating current a certain fundamental frequency is generated but in the transmission of telegraphic signals by means of a key, it is impossible to depress the key at the instant the generated current is zero which thereby produces harmonics of a magnitude and frequency considerably higher than the fundamental. The opening and closing of the circuit by means of the key 22 thereby produces what is termed transient currents which are very noticeable in the telephone circuit if the key is depressed when the current is of a value other than zero. These transient currents tend to produce in the telephone circuit suitably connected with the line disturbances which are very disagreeable to parties carrying on a conversation. The introduction of filters as before described thus tends to suppress these transients whereby the frequency of the current as actually transmitted to the line is of a uniform value, and there will not be present the higher harmonics which would be present if such were not provided. These transient currents also tend to unbalance the line and thereby render it difficult to accurately balance the same to take care of various changes in line condition.

The secondary coil of the transformer 24 is in a loop or network 52 which is somewhat similar to a Wheatstone bridge and comprises a coil of each of the transformers 24, 27 and 28 respectively. To that portion of transformer 27 which is in the bridge circuit 52 there is connected the usual artificial bal-

ancing network, and in order to simplify the circuit arrangement it has been omitted, but is however, represented by the rectangle 29. The mid point of one of the coils of the 5 transformer 27 is grounded through a retardation coil 30 for preventing the cross-fire of the direct current duplexes operating upon each of the wires 4 and 5 and also increases the transmission efficiency of the telephone circuit. There is connected across the zero potential points of this bridge, as viewed from the alternating current telegraphic transmission voltage standpoint, two circuit arrangements, one of which 10 serves as a means for receiving the alternating current telegraphic signals while the other is for the purpose of receiving and transmitting currents from such telephone apparatus as may be associated or connected therewith. In the telephone side which is 15 to the right of the dotted line 2-2 there is connected in each of the conductors 31 and 32 a resonant unit consisting of condensers 33 and 34 and inductances 35 and 36 respectively. There is also connected in bridge of these conductors, a unit comprising an inductance 37, and a condenser 38. These units have their inductances and capacitance so computed as to 20 suppress or exclude telegraphic signals and likewise to prevent them from being unduly absorbed by the composite or telephonic equipment associated with the line conductors. A repeating coil 39 has one coil 25 in circuit with these units while the other coil thereof is connected with the conductors 40 and 41. These conductors are suitably connected with the usual telephone equipment and since this does not form a part of 30 the present invention and is well known, it has been omitted from the drawing in order not to complicate the circuit arrangement.

The receiving means for the reception of 35 the alternating current signals, as shown to the left of the dotted line 2-2 is coupled to the network by means of a repeating coil 42. A winding of this repeating coil also forms a part of the network or loop circuit in which is connected in bridge a unit comprising 40 an inductance 43 and a condenser 44 together with a variable resistance element 45. The resistance element 45 serves to vary the strength of the incoming signals and which is technically termed "gain". This, therefore, provides for variations in the length of 45 the line over which the signals are being transmitted. The unit consisting of the inductance 43 and the condenser 44, the values of which have been computed, are for the purpose of suppressing any extraneous currents which may have been superimposed on the line conductors as well as rendering it substantially opaque to direct current signals. The inductance 43 is of a low value such as 50 approximately 1 henry while the condenser 55

44 is of a comparatively high value and the two when taken together therefore have a very low impedance value to currents of a frequency other than those generated at the alternating current source, while it readily allows currents of a frequency the same as that generated at the alternating current source to pass through to the alternating current receiving circuit. A loose coupling 60 50 is also suitably connected with the loop circuit mentioned above and connects the same with the various thermionic amplifiers for amplifying the signal waves. This loose coupling has two important functions, one being to increase the selectivity of the receiving circuit and the other to further render the circuit opaque to direct current signals.

The alternating current signal receiving circuit is made up of a number of vacuum 65 tubes or amplifiers such as 47, 48 which serve to amplify the received alternating currents, while the tubes 49 and 50 are for the purpose of converting the alternating current into pulsating and direct current impulses. The thermionic amplifier as herein employed is well known to those skilled in the art and a detailed description thereof is considered unnecessary. There is associated with the output of these amplifiers a Wheatstone polarized relay 51. The employment 70 of a relay of this character permits of a considerable amount of variation in the amplitude of the rectified alternating current signal without producing in the local 75 sounder or other receiving circuit an undue amount of distortion. A suitable sounder such as 60 is connected with the vibrating armature of the polarized relay 51 and serves as a means whereby an operator can detect 80 the signals as transmitted from a distant station.

The network 52 is coupled with the line 85 conductors 4 and 5 through the winding of a repeater coil 28. The middle point of one 90 winding thereof is grounded through a retardation coil 53 for preventing cross fire of the direct current duplex equipments operating on each side of the line conductors and also protects the phantom circuit from 95 serious transmission losses. A pair of condensers such as 54 and 55 are connected in the line conductors 4 and 5 respectively and serve to impede the flowing of direct current signals through the repeating coil 28. 100 The units 56 and 57 are connected in the circuit between the repeating coil 28 and the bridge to which the phantom circuit is connected, each comprising an inductance and a condenser for the purpose of preventing 105 the alternating telegraph carrier currents from interfering with the workings of the phantom circuit. It is thus seen that the currents as superimposed on the line conductors through the actuation of the key 110

22 are prevented from being unduly absorbed by the telephone equipment which may be suitably connected with the line.

In a system of this character various methods of signaling may be carried on simultaneously without danger of interfering with the other signals which at the same time may be transmitted over the line. The efficiency of each of the several channels of communication is in itself materially increased and at the same time the maintenance is necessarily decreased.

The operation of the system as hereinbefore set forth is as follows: Let us assume that both telegraphic carrier currents and telephone currents are being metallically transmitted over the conductors 4 and 5, the telegraphic signals being formed by means of the transmitting key 22 in circuit with the generator 21. These signals will be repeated to the transformer or repeating coil 23 passing through the inductances or resistances 25 and the condensers 26 to the transformer 24. Since the transformer 24 forms a part of the network 52 in which there is connected a transformer or repeating coil 28, the alternating current telegraph signals thereby pass to the line conductors 4 and 5 connecting a distant station. It is, of course, understood that the apparatus at the distant station is identical with that as shown in Fig. 1.

The placing of any bridge across the telephone circuit increases the crossfire interference between the direct current channels. To prevent this it is necessary to place a ground at the middle point of one of the coils of transformer 28. Since a simple ground at this point would operate as a short circuit to the phantom telephone circuit the inductance coil 53 is placed in this ground path and acts as a high impedance to the phantom telephone currents.

Since the telephone and alternating current signaling receiving circuit are connected to the zero potential points of the network 52 as viewed from the alternating current telegraph transmitting voltage standpoint, the working of these circuits will not be interfered with by currents emitted from the alternating current source at the station which is transmitting. The signals as transmitted from the transmitting set or a distant station pass over the conductors 4 and 5 in series and through the repeating coil 28 to the receiving circuit designed for this purpose. These signals pass through the inductance 58 which is tuned with the condenser 59 so as to be resonant to the alternating telegraphic current frequency and through the repeating coil 42 to the loose coupling 46. The signaling current however passes through the filter as made up of the inductance 43 and condenser 44 for the purpose of suppressing any extraneous cur-

rent. The resistance 45 is adjusted to impress on the thermionic amplifier a current of a strength dependent upon the length of the line extending between the two stations. The negative and positive portions of the wave as transmitted passes through the respective thermionic amplifiers where they are amplified and rectified, and then through the polarized relay 51 which controls through its contacts the operation of the receiving sounder 60. The receiving sounder 60 will thereby be operated in accordance with the incoming signals. The alternating current telegraphic signals are prevented from being unduly absorbed by the composite equipment or the telephone branch by means of the filters connected in this branch, as heretofore set forth.

In Fig. 2 there is shown the same arrangement as that of Fig. 1 with the exception of the method or manner of connecting the telephone branch with the line conductors 4 and 5. In this case the telephone branch of the composite equipment is connected with the line conductors through the repeating coil 61 to which the one side of the phantom circuit as 62 is taken off. The units 56 and 57 thereby serve to suppress or exclude the alternating current telegraph signals and prevents the same from interfering with the transmission of telephonic currents.

The operation of the system is identical with that as described in connection with Fig. 1, and a description thereof has been dispensed with for this reason.

Referring now to Fig. 3 and the embodiment illustrated therein, the method of connecting the telephone branch with the line conductors is the same as that of Fig. 2 and the difference lies in the method of connecting the alternating current receiving and transmitting circuit with the line. In this case, they are inductively coupled while it may be noted in the previous case they were directly connected with what was termed a bridged network or a Wheatstone bridge. The arrangement shown in this figure continues to limit the effect of the alternating telegraph currents in the telephone branches not by connecting this branch at points arranged to be at zero potential with respect to the alternating current transmitting voltage, but by relying wholly upon the use of filters in the line circuit for accomplishing this result. This method is also employed in the system as shown in Fig. 2. By providing the filters 56 and 57, composed of suitable inductance and capacitance, the potential of the alternating current source 21 need not be of as high a value as would be necessary if these units were omitted. This is due to the fact that the absorption of the alternating current signals by the composite equipment would be such as to require a higher poten-

tial to produce the same character of impulses on the line conductors 4 and 5, on account of the distortion which the signals will of course suffer. It thus becomes necessary to apply impulses of a higher potential to overcome the effect of such absorption. Obviously, then, the signals received at the distant end of the line conductors 4 and 5 would not be of the same wave form if the filters 56 and 57 were not utilized for preventing the undue absorption of the alternating current signals by the composite equipment. These units not only accomplish this result, but also render the direct current telegraph channel more efficient and positive in operation.

The alternating current signals are formed in the same manner as before described and are impressed upon the line through the repeating coil 63, one coil of which is grounded at its middle point for the purpose of equally dividing the currents between the two conductors, as well as limiting the effect of the crossfire of the direct current duplexes operating on the line conductors 4 and 5 respectively. The network 29 which is for the purpose of balancing the line, in connection with inductances 64 and 67, and the condensers 70 and 71 serve to balance the unit comprising the inductances 65 and 68, and the condensers 54 and 55 when considered with the line. These units, therefore, when taken together render the primary windings of the repeating coils 66 and 69 neutral with respect to the secondary windings thereof. In this way no potential is applied to the secondary windings of the repeating coils 66 and 69, and the receiving circuit is therefore unaffected by the transmission of alternating current signals.

Incoming alternating current telegraph signals therefore pass through the repeating coils 66 and 69 in the bridge connected with the line conductors. In bridge with the receiving circuit there is shown the inductance 43, condenser 44 and the variable resistance element 45 as before mentioned. This shunt is of extremely low impedance to currents of any frequency except that to which it is resonant and therefore serves to almost completely exclude from the alternating current receiving circuit interference currents due to the operation of the direct current duplex equipments on each of the line conductors. The remainder of the operation of the system is the same as that previously described.

It is often very desirous to be able to secure an additional duplex channel over a single line being operated either direct current duplex or simplex. An arrangement of this character is shown in Figs. 4 and 5 and will now be described. A line conductor such as 72 extends between two

distant stations and terminates at each of the stations in the circuit arrangement as shown in Figs. 4 and 5. The direct current duplex equipment is the same as that previously described and is connected with the conductor 72 through an inductance 75, one terminal of which is grounded through a condenser 76. These two when taken together serve to round off the peaks of the waves as transmitted from the direct current duplex equipment as well known in the art. A second inductance 77 is also connected in the line and has a condenser 78 in bridge thereof, the purpose of which will be more clearly understood from the description which is to follow. The alternating current transmitting circuit is inductively coupled with the line through a transformer 79, one of the terminals of the secondary coil thereof being grounded. There is also connected in the line various inductances and resistances 80, 81, 82 and 83 respectively, and the condensers 84 and 85 all of which are connected in series with the line and the artificial balancing network as at 86. The alternating current receiving circuit is connected across the terminals of the inductances 80 and 83 and is arranged as were the other circuits previously described with an inductance 43, condenser 44 and a variable resistance element 45 which serve the same purpose as before. The transformer 42 couples the line with the receiving polarized relay 51 through suitable amplifiers in the same manner as previously pointed out. The remaining part of the receiving circuit is identical with that as previously described.

A telephone branch such as 87 is coupled with the line through a repeating coil 88 having a terminal at one of the windings thereof grounded inasmuch as a single conductor is employed. The repeating coil 88 is connected with the line through suitable inductances and condensers. In order to prevent the flow of alternating telegraph signals through the telephone branch, the inductance 77 and condenser 78 have been inserted in the line.

The arrangement as shown in Fig. 5 is the same as that of Fig. 4 with the exception of the method of connecting the alternating current telegraph receiving circuit with the line. In the latter figure the receiving circuit is directly connected with the line while in the former it is inductively connected. The operation of the two systems is identical and a detailed description thereof is thought to be unnecessary.

What is claimed is:

1. In a telegraph system, a metallic line circuit connecting two stations, means for simultaneously transmitting both direct and alternating current telegraph signals over said line circuit, a composite set connected

- 6 to said line circuit, telephone equipment associated with said composite set, and means comprising a set of filters for preventing the superimposing of said alternating current signals on currents in said composite set.
2. In a telegraph system, a metallic line circuit, a source of alternating current of a predetermined frequency, means for transmitting telegraph signals over said line circuit from said source, a composite set associated with said line circuit comprising inductance and capacitance, telephone equipment connected to said composite set, and parallel resonant units serially connected in said line circuit for preventing the absorption of current from said source by said composite set.
3. In a telegraph system comprising a line conductor, a source of alternating current, means for transmitting telegraph signals from said source, means for receiving such signals, a transformer for coupling said receiving means with said line, and means consisting of an inductance shunted by a condenser connected in bridge of a winding of said transformer for excluding from said receiving means extraneous currents.
4. In a telegraph system, a line conductor, a source of alternating current, a key for transmitting telegraph signals from said source, means for receiving such signals, an inductive coupling between said receiving means and said line, and means comprising an inductance and a condenser of comparatively low and high value respectively, connected in bridge of said inductive coupling for excluding from said receiving means
- signals transmitted from a source other than that of said alternating current source.
5. In a signaling system of composite telephony and telegraphy, a metallic line circuit joining two stations, a source of alternating current of a frequency of approximately 80 cycles, means for transmitting telegraph signals from such source, a composite set, telephone apparatus associated with said set, and an anti-resonant circuit interposed between said alternating current source and said composite set for preventing the absorption of said 80 cycle current by said composite set.
6. In a signaling system of composite telephony and telegraphy, a metallic line circuit joining two stations, a source of alternating current of a frequency of approximately 80 cycles means for transmitting telegraph signals from such source a composite set, telephone apparatus associated with said set, and a parallel resonant unit associated with said composite set for preventing the absorption of said alternating current signals by said composite set.
7. In a telegraph system, a line, a source of alternating current, means for transmitting telegraphic signals from said source, an induction coil inductively connecting said source of current with said line, and means interposed in the line between said induction coil and said source of current and effective due to the transmission of telegraphic signals for suppressing disturbing harmonic frequencies.

In witness whereof, I hereunto subscribe my name this 16th day of December A. D., 1919.

GEORGE C. CUMMINGS.
